UNITED STATES PATENT OFFICE.

ARTHUR I. RISSE, OF CHICAGO, ILLINOIS, ASSIGNOR TO U. S. BOTTLE MACHINERY CO., OF CHICAGO, ILLINOIS, A CORPORATION OF ILLINOIS.

BOTTLE-FILLING MACHINE.

Application filed May 31, 1922. Serial No. 564,913.

To all whom it may concern:

Be it known that I, ARTHUR I. RISSE, a citizen of the United States, residing at Chicago, in the county of Cook and State 5 of Illinois, have invented a certain new and useful Improvement in Bottle-Filling Machines, of which the following is a specification.

This invention relates to automatic machines for filling each one of a series of bottles, passed through the machine, to a pre-determined height.

The object of the invention is to provide such a machine in which the bottles always 15 travel in substantially the same horizontal plane, thereby doing away with the opportunity for injury which arises in machines of the prior art in which they are elevated and depressed during the filling operation.

The further object of the invention is to provide a siphon-bottle-filling mechanism which automatically seals itself without the use of movable valves during the time it 20 has to be out of liquid in entering and leaving the bottle to be filled.

The invention consists in mechanism for attaining the foregoing and other objects hereafter set forth in the specification and claim, which can be easily and cheaply 25 made, which is satisfactory in use and is not readily liable to get out of order.

Referring to the drawings in which like numerals designate the same parts throughout the several views:

Figure 1 is a section, showing a machine embodying this invention in its preferred form, the same being taken on the line 1—1 of Figure 3.

Figure 2 is a face view of the upper part 40 of the machine taken from the position 2—2 of Figure 3.

Figure 3 is a plan view of the machine taken just below the frame member 60, hereafter described.

Figure 4 is a sectional end view on the line 4—4 of Figure 3.

Figure 5 is a sectional view of the siphon

mechanism with the siphon tube raised for the insertion or removal of a bottle.

Figure 6 is a changed position view of 50 the parts of Figure 5 as they appear when bottle filling is actually taking place.

Figure 7 is a perspective view of the siphon mechanism removed from other parts of the device.

Rising from the factory floor or other suitable support 10 is a table frame 12, having journalled in its center a vertical shaft 14, carrying a rotatable table top 16, and adjacent to this table frame 12 is another 60 elongated frame 18, having mounted in it for horizontal travel the continuous belt or conveyer 20, propelled by a suitable source of power beyond Figures 3 and 4 (not entering into this invention and therefore not 65 shown in detail). The upper section of this horizontal belt is conventionally mounted upon a set of rollers 22 which maintain it substantially level in all positions of movement, while the lower part of the belt travels over a large pulley 24 and is held in place thereon by the auxiliary rollers 26.

Inside this pulley 24 is a conventional clutch mechanism 28 of any conventional form, having clutch arms 30 engaging a 70 clutch cone 32 conventionally operable by hand lever 34 in such manner that the rotary movement of pulley 24 may be selectively communicated to shaft 36 journalled in frame 18 and 12 and carrying on its end 75 in frame 12 a bevelled pinion 38 meshing with a gear 40 on shaft 14, whereby, when lever 34 is moved to have pulley 24 rotate shaft 36, the shaft 14, and consequently table 16, is rotated thereby. Conveyer belt 80

20 is of sufficient width so that one or more bottles 42 may be placed upon its upper surface at one side of the machine and, except as hereafter specified, carried entirely 85 across the frame 18 to the other side of the machine. But, in actual operation, this direct course of travel with the belt 20 is interrupted in proximity to the table top 16

90 by a curved intake trackway 44—46 which,

assuming that bottles are traveling from left to right across Figure 3, compels the bottles to travel off from the belt 20 and onto the table top 16 and by the delivery trackway 48-50, which causes bottles—which have made substantially a complete circuit of the table 16—to return to the belt 20 and complete their path of travel on belt 20 to the extreme right hand side of the machine.

10 Table top 16 carries in its center a liquid supply tank 52, preferably but not necessarily of circular cross section, the same being surrounded on its outside by a bottle rack 54, having in its circumference notches 56—in the particular case here illustrated semi-circular ones, adapted to fit the contour of the particular type of bottle which is to be handled by the device. The tooth relationship of the gear members 38 and 40 15 is such that, as the belt or conveyor 20 forces bottles through the trackway 44-46 onto the table top 16, they move one by one into the notches 56 moving into place to receive them, with the result that the bottles will be carried by the table top 16 in a uniform circular path around the central axis of shaft 14, as clearly indicated in Figure 3.

Rigidly sustained above and parallel to rotatable table 16 by suitable rods or posts 30 58 is an annular frame 60 of approximately the same diameter as member 54. This ring 60 has in its outer circumference a plurality of suitably formed vertical slots 62, each traversed by a vertical bar 64, equipped at 35 its lower end with an attaching mechanism 66, by means of which the siphon mechanism of Figures 5-7 may be detachably secured. Each bar 64 has journaled upon it a cam roller 68 adapted to travel on a semi-circular cam 70, having downwardly inclined ends 72 and 74. This cam 70 is stationarily supported by any conventional mechanism—as, for instance, the upper portions of upright frame members 12 which, as 40 shown, extend high enough to carry a top member 76, over which a horizontal water pipe 78 passes, to a valve 80 and down spout pipe 82 designed to deliver liquid supplied from any suitable source, through pipe 78, 45 to the tank 52.

The siphon, which is attached to the bottom of each rod 64, may—so far as the parts thus far described are concerned—be of any conventional form. The particular one 50 shown happens to be made of three pieces:—the U-shaped member 84 and two vertical members 86 and 88, the parts being of such a size that the member 86 is adapted to enter the neck of the bottle to be filled and that the member 88 is adapted to enter the tank 52.

In the preferred form of the construction shown in the drawing, the lower end of member 86 is closed by conical member 90, designed to readily guide the lower end of

member 86 into the bottle 42 below it. In the side of member 86, and immediately adjacent to this conical member 90, is a port 92 coverable and in the position of Figure 5 closed by a tube 94 slidable on pipe 86. The 70 lower end of member 94 fits closely against the base of cone 90 to form a seat 96, so that when the parts are in the position of Figure 5, it is impossible for any liquid to pass the tube 94 to or from pipe 86. Rigidly mounted 75 on tube 94 is a block 89 adapted to in the position of Figure 6 rest on the top of the bottle 42, and thus hold tube 94 stationary with reference thereto while the pipe 86 moves into the bottle to the position of Figure 6 to thereby open the port 92.

Suitably mounted at a predetermined point on the lower end of pipe 88 and enclosing it for some distance from its bottom is a cup 100 adapted in all positions of the device to keep a definite quantity of liquid 102 on this lower end of pipe 88, thereby insuring the siphon mechanism's retaining sufficient liquid throughout its entire length so that when the parts are in the position of Figure 5, a slight leakage may take place through port 92 and valve seat 96 in the other arm of the siphon without the siphon losing its liquid and thereby destroying its operativeness when it is next moved to the position of Figure 6 as hereinafter described.

This tank 100 is of great importance in this invention because it does away with a valve mechanism at the lower end of pipe 100 88 analogous to the valve at the lower end of pipe 86 and the mechanism which would have to be installed in or adjacent to the tank 52 to open such valve mechanism when the lower end of pipe 88 enters the liquid 102 in tank 52. It is because of the absence of a mechanism doing what this tank 100 does that it has heretofore been practically impossible to operate a device of this character in which the bottles travel only in a 110 horizontal plane as they do in this device.

The siphon devices of Figures 5 to 7 are so mounted on the bars 64 that the tanks 100 lie in a circle around the inside of tank 52 as clearly shown in Figure 3. Inside the circle of cups or tanks 100 and perforated to slide vertically on pipe 82, in a float 106. Slidable vertically on the bottom portion of pipe 82 is a cup pipe 108 having a side port 110, closed, in the position of Figure 1, but automatically opened when it moves down beyond the lower end of pipe 82. This pipe 108 carries a vertically adjustable collar 111 having on it a projecting clamp 112 or other lug adapted to be engaged by the upper 125 edge of the float 106 so that said float as it moves upward under the influence of a rise in the level of liquid supplied to tank 52 through pipe 82 and port 110 carries pipe 108 up high enough to close port 110 and 130

prevent further flow of liquid from pipe 82 into tank 52. It is obvious that by selectively adjusting collar 111 on pipe 108, the operator can determine the location of water level 114 in tank 52 and thereby determine the height to which bottles 42 are filled.

In operation of the entire mechanism, the operator first makes the adjustment just described, so that the float 106 will shut off the supply of liquid delivered through pipes 78-82 to the tank to maintain the level 114 at the proper point to properly fill the bottles which are to be passed through the machine. In actual practice as the machine operates, there is a continuous, step by step movement of this valve 108, admitting liquid to the tank 52 to maintain this level 114, as the bottles on the table are being filled in the manner hereafter described.

Having adjusted the float mechanism to thus properly maintain the level for the bottles which are to be filled, the bottles 42 are placed by an operator on the left hand end 25 of belt 20 which carries them, in the manner described, to the trackway 44-46 through which it forces them onto the rotating table 16 where they fit one at a time into the notches 56 directly under the conical members 90 of the siphon devices heretofore described. When once in place on the table, they are carried completely around it until they are switched off from it by the trackway 48-50 and thence carried by the belt 30 to the right hand side of the machine where they are removed for corking or other handling as may be desired.

While the bottles 42 are on the front, viz.: lower half of table 16, as viewed in Figure 40 3, the rollers 68 controlling the siphon devices for those particular bottles are traveling on the main part of cam 70 and, therefore, the siphon devices for those particular bottles are in the position of Figure 5 which 45 allows the bottles to slip into place on the table under the guidance of trackways 44-46, or to leave the table under the guidance of trackways 48-50, as the case may be, without interference from these siphons. As 50 soon, however, as a bottle, placed on the table by trackway 44-46, passes below cam track end 74, the roller 68, controlling the siphon for that particular bottle, travels down that trackway thereby allowing the 55 siphon for that bottle to move by gravity from the position of Figure 5 to that of Figure 6 in which cup 100 enters the liquid of the tank; the block 89 rests on the neck of the bottle and port 92 opens. The minute 60 the parts assume this position, the siphon starts to operate in ordinary manner to cause liquid to flow over the edge of cup 100 into pipe 88; thence through member 84 down pipe 86 and through port 92 into the bottle. 65 The machine travels slow enough so that as

the bottle travels around the rear half of the table, viz.: its upper half, as shown in Figure 3; there is sufficient time for enough liquid to travel from the tank 52 into the bottle to fill it to the level determined by the float mechanism 106, heretofore described. When, now, the bottle in its travel on the table 16 passes under cam track end 72, the roller 68—controlling the siphon mechanism of that particular bottle—travels up this member 72 to track 70 thereby moving that particular siphon from the position of Figure 6 to that of Figure 5 and thus getting it out of the way of the upper end of the bottle so that the bottle can be carried off from the table by trackway mechanism 48-50.

As the cam 72 operates, as just described, and lifts the siphon mechanism from the position of Figure 6, the cup 100 fills itself with liquid 102, thus sealing the lower end of pipe 88 so that it is impossible for the siphon to discharge and lose itself through pipe 88 in the manner which anyone skilled in the art will understand would be the case were no seal provided at this point. During this same upward movement of the siphon, pipe 86 is drawn upward in tube 94 until port 92 is closed by tube 94, thus making a practical seal of the siphon at this point. 95 As the lower arm of pipe 86 is considerably below the upper surface of liquid retained in cup 100, the siphon cannot destroy itself, viz.: have all the liquid run out of it, until there has been sufficient leakage through port 92 to admit air enough to destroy the siphon in conventional manner. In actual practice, there is not sufficient time for this leakage to occur through port 92, if slightly defective, while the table 16 is making a half revolution, the result being that in practice, the siphons do not fail to work and no bottles pass through the machine without being filled with liquid, as is the case with devices where the siphon can destroy itself 100 during the period that it is not in engagement with the bottle to be filled.

One special feature of advantage of the machine lies in the fact that if for any reason a siphon and its bottle fail to register with each other so that the siphon enters the bottle as described, and, on the other hand the bottle holds the siphon up in the air, so to speak, as it travels the circuit of the table, no damage can result because the siphon mechanisms are moved downward by gravity only on the frame 60; that is to say, there is no rigid downward forcing mechanism to be broken when the siphon fails to enter the bottle as it should.

What I claim is:

In a bottle filling machine, a frame, a turn table mounted on said frame between the upper and lower ends thereof, a tank supported by the turn table, uprights rising 130

from said turn table, a ring supported by said uprights in spacement above the tank and concentric with the turn table, vertically extending guideways carried by the ring, bars slideable in said guideways respectively, a siphon mechanism carried by each bar, a rail carried by the frame and extending partly around said ring, said rail having

downwardly inclined terminals, and a roller on each of said bars coacting with said rail during rotation of the turn table to raise and control lowering of the bars and said siphon mechanisms. 10

In witness whereof, I have hereunto subscribed my name.

ARTHUR I. RISSE.
